UNITED STATES PATENT OFFICE.

ALEXANDER MCLEAN NICOLSON, OF NEW YORK, N. Y., ASSIGNOR TO WESTERN ELECTRIC COMPANY, INCORPORATED, OF NEW YORK, N. Y., A CORPORATION OF NEW YORK.

PIEZOPHONY.

Application filed April 10, 1918. Serial No. 227,802.

To all whom it may concern:

Be it known that I, ALEXANDER MCLEAN NICOLSON, a subject of the King of Great Britain, residing at New York, in the county of New York and State of New York, have invented certain new and useful Improvements in Piezophony, of which the following is a full, clear, concise, and exact description.

As indicated in the *Handbuch der Physik*, Vol. IV, p. 774, 1905, Piezo-electricity by F. Pockels, it was recognized as early as 1880 by J. and P. Curie that on subjecting the opposite sides of certain crystals to pressure, a difference in electrical potential at certain sides of the crystal is produced. This difference in potential was relatively small and was determined by an electrometer. The early investigators in the field of piezo-electricity or pressure-electricity experimented with different kinds of crystals and observed that this piezo effect was pronounced in a crystal of sodium potassium tartrate. This prior work was entirely experimental and no practical use was made of this interesting phenomenon.

According to the present invention, it has been discovered that piezo-electric crystals and especially those of sodium potassium tartrate are admirably adapted for use in telephone transmitters and receivers, repeaters, loud speakers, generators and modulators of alternating currents and the like. It has been discovered that piezo-electrical crystals may be used to particular advantage in submarine signaling or for the detection of hostile submarines. It has also been discovered that these crystals when placed on the ground or on some object in contact with the ground such as a rock, tree, or the like, are extremely sensitive to an earth tremor caused, for instance, by a person walking in the proximity of these crystals. This latter use of these crystals is of particular advantage in trench warfare.

An object of the invention is to provide piezo-electric devices adapted to the above and similar uses, and methods of operating the same, as will be indicated in the following detailed description taken in con-

nection with the drawings, in which Fig. 1 illustrates a cross section of a piezo-crystal that may be employed; Fig. 2 is a perspective of the crystal shown in Fig. 1; Figs. 3 and 4 illustrate a crystal provided with electrical connections; Figs. 5, 6 and 7 show the adaptation of these crystals to loud speakers or receivers; Fig. 8 illustrates a crystal mounted in a watertight tube and adapted to be employed for submarine signaling; Fig. 9 illustrates a system employing a piezo-electrical transmitter, repeater and receiver; Fig. 10 illustrates a repeater circuit employing piezo-electric devices; Fig. 11 illustrates the adaptation of a piezo-electric crystal for carrier current signaling; and Fig. 12 illustrates the use of a piezo-electric crystal for detecting mining operations in trench warfare.

The following very brief description will be given of the method described in my co-pending application, Serial No. 226,343, filed April 2, 1918, Patent No. 1,414,370, granted May 2, 1922, for preparing a crystal in which the piezo-electric effect is very pronounced.

A small crystal of sodium potassium tartrate, shown in cross section at 1 in Fig. 1, is placed in a concentrated solution of its mother liquor. This concentrated solution is very slowly cooled and the crystal grows until it attains the relative size shown in the drawing 1' and weighing, in some instances, as much as one pound. As set forth in application 226,343 referred to above, the crystal is preferably supported in the mother liquor on a platform above the bottom of the solution, and when so grown the bottom of the crystal will usually be reentrant, as shown in Fig. 1, which form increases the piezo-electric effect in the crystal. The full-grown crystal is dried, soaked in alcohol for a few hours, again dried and provided with a waterproof coating, for instance of wax. The electrical resistance as well as the natural frequency of the crystal made in accordance with the above process depends upon the amount of moisture that is permitted to enter or leave the crystal, and in order to stabilize the electrical constants of the crystal it is provided with

a waterproof coating such as ambroid or wax, as illustrated in Fig. 4.

The electrical connections to the crystal may be made by the conductors 4 and 5 (Fig. 3), these being soldered to the crystal by means of the extended surfaces 6 and 7 of Wood's metal which has a melting point about the same as that of the crystal. Electrical connections are also made to the crystal by means of the conductors 8 and 9 which are attached by means of Wood's metal or other fusible alloy to the tin foil sheets 10 and 11 which are cemented with ambroid to the opposite sides of the crystal. In order to increase the dielectric strength of the crystal a sheet 12 of a dielectric such as mica is provided between one of the tin foil sheets 11 and the adjacent side of the crystal. This is used to best advantage when considerable electrical power is impressed upon a crystal for instance when it is operating as a receiver, the current consumed by the crystal being largely a displacement current.

It is not possible to predetermine the best manner of connecting the crystal in circuit and this should be determined by trial. As a rule, only two of the four conductors shown in Figs. 3 and 4 will be used and those two conductors that give the best result may be easily determined. In general, it will be found that the best results may be obtained by connecting from conductor 9 to either conductor 4 or 5, but in other cases best results may be obtained by connecting from conductor 8 to either conductor 4 or 5. Another arrangement that gives very good results is to connect the conductors 8 and 9 together, using them as a common conductor and also employing either of the conductors 4 or 5.

Fig. 5 illustrates a loud speaker or receiver in which the two crystals 13 and 14 have their opposite ends fastened to the common bases 15 and 16. The crystals 13 and 14 may be suitably fastened to bases 15 and 16, for instance, by means of the Wood's metal, as previously described.

It has been found that a crystal made as indicated above responds in a greater degree to currents of some frequencies than to currents of other frequencies. Each such crystal will in general have a plurality of resonant peaks depending upon the crystal's growth, structure, curing, etc. In some crystals all of the resonant peaks have been found to lie in a frequency zone of 300 to 10,000, and in others this zone may lie above 10,000 and extend to 100,000. As there are so many factors which determine the frequency characteristics of a crystal, it is difficult to obtain crystals having identical frequency characteristics. It is possible to modify the position of the zone of resonance points for instance by varying the period of

desiccation of the crystal. The longer the crystal is desiccated, the higher up in the scale will the zone of resonant peaks lie.

Advantage is taken of the fact that the frequency characteristic of one crystal may be made different from that of another by employing a plurality of crystals, each one of which has resonant peaks not found in the other. The crystals should be free to vibrate independently and should be connected in series as shown in Fig. 6. It has been found that this arrangement gives an improvement in the quality of response as well as an increase in the intensity of response, when employed as transmitters or receivers.

Fig. 6 illustrates a loud speaker or receiver in which the crystals 17 and 18 at the bottom ends thereof are attached to a common base 19, the upper ends being provided with individual bases 20 and 21.

Fig. 6 illustrates a modified form of the manner of making the electrical connection to the crystals which are, in this case, provided with girdles 22 and 23 of tin foil. The crystals shown in Figs. 3, 5, 6 and elsewhere may be provided with a moisture-proof coating such as wax or ambroid, as shown in Fig. 4.

Fig. 7 illustrates a loud speaker or receiver in which the crystals 24 and 25 have their opposite ends fastened to the extended surfaces 26 and 27 in a manner similar to that shown in Fig. 5. In this case the crystals are surrounded by the fibre cylinder 28, between one end of which and the member 26 is a rubber ring 29. The cylinder 28 and ring 29 form the wall of a container, the inside of which may be filled with a suitable semi-elastic compound such as wax, as shown at 30. The cylinder 28 and the elastic ring 29 provide an elastic connection between members 26 and 27 which permits the crystals 24 and 25 to expand and contract longitudinally. It is obvious that any number of these crystals may be employed and two are shown only for the purpose of illustration.

Assume a single piezo crystal connected to an electrometer. If a weight is placed on the crystal the variation in compression of the crystal produces an electrification resulting in a deflection of the electrometer needle in a given direction. When the weight is removed the compression is relieved, resulting in a reversal of electrification and likewise of deflection. In this way it is possible to determine the polarity of a crystal; for instance, an electrode of the crystal may be arbitrarily called a positive electrode if the removal of the weight produces a positive deflection of the needle when that electrode is connected to a given electrometer terminal. If the devices shown in Figs. 5, 6 and 7 are to operate as transmitters, that is, as generators of current, obviously the crystals should be con-

nected in circuit so that the potentials generated will be additive and not subtractive.

If current is supplied to a crystal it will produce either a longitudinal expansion or contraction of the crystal. If the devices of Figs. 5, 6 and 7 are to operate as receivers, preferably when current is supplied to the crystals, they should both expand and contract in synchronism; i. e., when one expands the others should also be expanding, so that their effects will be additive for receiver action. As in the case of the transmitter, the proper connection of the crystals may be made either by trial or after predetermining the polarity of the crystals, which are then connected in the manner in which batteries would be arranged in series or in parallel.

In the device shown in Fig. 8, which is adapted to be used for submarine signaling, the crystal 31 has its opposite ends soft soldered to the inside wall of the metal tube 32. The crystal 31 is surrounded by waterproof material such as oil shown at 33, and retained within the tube by means of stoppers 34.

The operation of the piezo-devices shown in Figs. 1-8, either as transmitters or as receivers, will be explained in connection with Fig. 9 in which sound waves impinging upon the extended pole 35 of the crystal transmitter produces a corresponding variable electric current which the transmitter 36 supplies to the repeater 37. The variations in electric current supplied at the input circuit 38 of the repeater 37 produces a contraction and expansion of the piezo-crystal forming a part of this repeater, and this variation in the dimensions of this crystal produces corresponding variations in the electric current supplied to the output circuit 39 of the repeater and these electric currents in turn produce a variation in the dimensions of the receiver 40, causing its poles 41 to vibrate, thereby reproducing the sounds which were emitted adjacent the transmitter 36.

In Fig. 10 the current produced by the transmitter 42, which is adapted to be actuated by sound waves, is supplied to the control electrode 43 of the space current device or audion 44. The transmitter 42 is very well adapted to be directly connected to the input circuit of the audion 44 because both of these have similar and practically infinite impedances. The amplified currents delivered by the audion 44, which in this case operates as an amplifier, may be connected to the electromagnetic receiver 45 or to the piezo receiver 46.

In Fig. 11 the piezo device 47 is actuated by both the signal and by high frequency impulses and effects a modulation of the high frequency waves in accordance with the signal. Connection is made from de-

vice 47 by way of conductors 48 and 49 to the input circuit of the audion 50, and a portion of the amplified currents appearing in the output circuit of this audion are fed back by means of conductors 49 and 51 to the device 47. Since the input and output circuits of the audion 50 are coupled together through the device 47, this circuit will generate oscillations and their frequency will be sufficiently high for these currents to be employed as carrier currents for radio signaling or for wired wireless. The amplitude of the high frequency current generated is varied in accordance with the sound waves impinging on the device 47, and the modified high frequency impulses may be delivered to the outgoing line 52.

A piezo transmitter, such as shown in Fig. 8, may be placed in contact with the ground at 53 (see Fig. 12) in order to detect earth tremors such as caused by digging for the purpose of placing a mine. Electrical conductors may extend from the transmitter 53 to a suitable position in the trench where the receivers 54 are provided.

The invention is not limited to the details of the disclosure, but can be realized in widely different embodiments within the scope of the claims.

What is claimed is:

1. A piezo-electric crystal, a sheet of metal adapted to be fastened thereto, and a dielectric between said sheet and said crystal.

2. A crystal, and metal having substantially the same melting point as said crystal soldered to said crystal.

3. A piezo-electric crystal and an electrical conductor surrounding said crystal.

4. A piezo-electric crystal and extended surfaces attached to the opposite ends of said crystal.

5. A telephone instrument comprising a substance for transforming one kind of energy into another, one of said energies being the energy of sound waves, said substance being capable of generating a current in response to a change in pressure.

6. A telephone instrument comprising a crystal of sodium potassium tartrate.

7. A telephone instrument comprising a crystal of sodium potassium tartrate, and a moisture-proof coating therefor.

8. A telephone transmitter comprising a crystal capable of generating a current in response to a change in pressure, and a sound receiving element fastened to said crystal.

9. The combination of means for transforming one kind of energy into another, one of said energies being electrical and another being acoustical, a space current device having a control member, and a connection between said means and said device,

- said means comprising a substance capable of generating an electromotive force in response to a change in pressure.
10. The combination of a telephone transmitter comprising a crystal capable of generating a current in response to a change in pressure, an electron discharge device having a control electrode, and a connection between said crystal and said electrode.
11. A piezo-electric crystal having a plurality of faces electrically connected together.
12. Means for translating acoustical energy into electrical energy, a space current device having a control member, and a connection between said means and said device, said means comprising a substance capable of generating electromotive force in response to a change in pressure.
13. A wave transforming device comprising a substance for transforming one kind of energy into another, one of said energies being the energy of sound waves, said substance being capable of generating electromotive force in response to a change in pressure.
14. A sound wave transforming device comprising a substance for transforming energy of sound waves into electrical energy, said substance being capable of generating an electromotive force in response to a change in pressure.
15. A wave transforming device for transforming one kind of energy into another, one of said energies being the energy of sound waves, said device comprising a crystal of sodium potassium tartrate.
16. A sound wave transforming device for transforming the energy of sound waves into electrical energy, said device comprising a crystal of sodium potassium tartrate.
17. A translator of energy comprising a piezo-electric crystal having a reentrant pole-face.
18. A translator of energy comprising a piezo-electric crystal having a principal axis and two axes at right angles thereto, said crystal having a reentrant surface parallel to said principal axis.
19. A wave transforming device for transforming one kind of energy into another, one of said energies being the energy of sound waves, said device comprising a piezo-electric crystal having a reentrant pole-face.
20. A wave transforming device for transforming the energy of sound waves into electrical energy said device comprising a piezo-electric crystal having a reentrant pole-face.
21. A wave transforming device for transforming the energy of sound waves into electrical energy, said device comprising a piezo-electrical crystal of sodium potassium tartrate and said crystal having a 65 principal axis and two axes perpendicular thereto and having a reentrant pole-face parallel to said principal axis.
22. A wave transforming system for transforming one kind of energy into another, one of said energies being the energy of sound waves, said system comprising frequency selective means including a substance capable of generating an electromotive force in response to a change of pressure: 70
23. A whole piezo-electric crystal having a principal axis and two shorter axes perpendicular thereto, one of said two axes being about four or more times as long as the other. 75
24. A whole piezo-electric crystal of sodium potassium tartrate having a principal axis and two shorter axes perpendicular thereto, one of said two axes being about four or more times as long as the other. 80
25. The method of operating a body comprising a substance capable of generating electromotive force in response to elastic deformation and capable of the converse action, said body being resonant at an audible frequency, which comprises elastically deforming said body by the application thereto of energy waves of a frequency in the neighborhood of said resonance frequency. 85
26. The method of operating a body comprising a substance capable of generating electromotive force in response to elastic deformation and capable of the converse action, which comprises elastically deforming said body by the application thereto of energy waves of an audible frequency in the neighborhood of a frequency of maximum responsiveness of said body and taking off from said body electromotive force waves of said frequency. 90
27. In combination, a body comprising a substance capable of generating electromotive force in response to elastic deformation and capable of the converse action, said body being resonant at an audible frequency and a source supplying thereto energy waves for causing elastic deformation thereof, said waves having a frequency in the neighborhood of said resonance frequency. 95
28. In combination, a mechanical vibratory system comprising a substance capable of generating electromotive force in response to elastic deformation and capable of the converse action, a source supplying to said substance energy waves for causing elastic deformation thereof, said waves having an audible frequency in the neighborhood of a resonance frequency of said system, and means for taking off from said system electromotive force waves. 100
29. The method of operating a body comprising a substance capable of generating electromotive force in response to elastic de- 105
- 110
- 115
- 120
- 125

formation and capable of the converse action, which comprises elastically deforming said body by the application thereto of energy waves of a frequency within the voice range, 5 and taking off from said body electromotive force waves the frequency of which is a function of said frequency of deformation.

30. The method of operating a body comprising a substance capable of generating 10 electromotive force in response to elastic deformation and capable of the converse action, which comprises elastically deforming said body at a frequency within the voice range and taking off from the body electromotive 15 force waves of said frequency of deformation.

31. A wave transforming device comprising a substance for transforming one set of energy waves of an audible frequency into 20 another set of energy waves, said substance being capable of generating electromotive force in response to elastic deformation and capable of the converse action, and means for translating and utilizing said last mentioned 25 energy waves.

32. In combination, a piezo-electric crystalline body, a dielectric sheet on one face thereof, and means for creating a potential difference between the outer face of said 30 sheet and another face of said body, said

means operating to produce elastic deformation of said body.

33. A translator of energy comprising a piezo-electric sodium potassium tartrate crystal having a reentrant pole face. 35

34. The method of generating elastic vibrations of audible frequency in a medium capable of transmitting them in which a crystal is placed effectively in contact with said medium, which comprises generating an electrostatic field varying in accordance with the frequency of the vibrations to be produced, and subjecting said crystal to the action of said varying field. 40

35. Apparatus for the generation of sound waves, comprising a crystal, extended electrode surfaces in proximity to different faces of the crystal, and a source of audible frequency alternating current connected to 45 said electrode surfaces. 50

36. Apparatus for the generation of sound waves, comprising a crystal of sodium potassium tartrate, extended electrode surfaces in proximity to different faces of the crystal, and a source of alternating current connected to 55 said electrode surfaces.

In witness whereof, I hereunto subscribe my name this 2nd day of April A. D., 1918.

ALEXANDER McLEAN NICOLSON.
